INVENTOR.
Benjamin Escovar
BY
John H. Pollock
ATTORNEY

UNITED STATES PATENT OFFICE.

BENJAMIN ESCOVAR, OF CARACAS, VENEZUELA.

MECHANICAL APPLAUDER.

Application filed May 24, 1928. Serial No. 230,154.

This invention relates generally to applauders, and has more particular reference to a mechanical applauder for use in theatres and on occasions for replacing hand clapping.

5 The invention has for an object the provision of a device of the class mentioned which is of simple durable construction, desirable and efficient in action, and which can be manufactured and sold at a reasonable 10 cost.

The device proposes the use of a body member to which a pair of clappers are attached, one on each side thereof, so that the device may be conveniently operated with one 15 hand. Preferably the body member and clappers should be of wood, thin pieces, and held pressed together by a chain which may be removed from its engaged position to a rest position upon a handle connected with the 20 body member. Instead of wood, hard vulcanized rubber of many colors may be used.

Ornamentations are painted or burnt onto the device so that the colors do not come off. They may also be applied with luminous 25 paint for shining in the dark. On the outer side of one of the applauders a mirror within a frame may be secured, also ornamented with phosphorescent luminous paint.

The clappers should be joined to the body 30 by pieces of decorated leather or other flexible material. The handle may be ornamented in relief and suitably colored. The said chain should be of two sections joined by a clasp which may be provided with precious 35 stones.

For further comprehension of the invention, and of the objects and advantages thereof, reference will be had to the following description and accompanying drawings, and 40 to the appended claims in which the various novel features of the invention are more particularly set forth.

Fig. 1 is a front side perspective view of a device constructed according to this 45 invention.

Fig. 2 is a rear side perspective view thereof with the chain in lowered position.

Fig. 3 is a similar view with the chain in the process of being moved from its down- 50 ward position.

Fig. 4 is an edge elevational view thereof.

Fig. 5 is a detailed view of the chain clasp.

Fig. 6 is a fragmentary vertical sectional view, taken on the line 6—6 of Fig. 1.

Fig. 7 is a view similar to Fig. 3, but illustrating a modified form of the device.

The reference numeral 10 indicates generally a body member provided with a handle portion 12, preferably made of one integral piece of wood, or hard rubber, or the like. 60 Clapper members 14 are recessed as at 15 and flexible members 16 are attached to the clapper members within the recesses 15 and to the handle 12.

One of the clapper members 14 has a recess 65 17 on its outer side in which a mirror 18 is disposed, shock absorbing material 19 being placed between the mirror 18 and the clapper 14 for damping the transmission of shocks to the mirror. A frame 20 serves to hold the 70 mirror 18 in place.

The frame 20 is ornamental as indicated at 21, and ornamentation 22 is applied to the outer side of the other clapper 14. The handle 12 is also ornamented as indicated by 75 numeral 23.

A clasp 24 or 24' joins the chain sections 25 together, and the free ends of these sections are pivotally connected on the handle 12 and on opposite sides thereof, and arranged for engaging over the tops of the clappers and the body for pressing the clappers together into inoperative positions, and for engaging over the lower extremity of the handle 12 for holding the chain in an inoperative 85 position.

The modified form of the device shown in Fig. 7 discloses grooves 26 formed in the top of the clappers 14', and a groove 27 formed in the bottom of the handle 12' for engagement by the chain. One end of the chain 25 is attached to a slide member 28 engaged in a guide 29 secured on the member 16. Oppositely acting springs 30 act upon the slide member 28 for holding the slide member in 95 central position. The slide member 28 may be manually forced to a top position in the guide 29 when the chain 25 is engaged in or removed from the grooves 26, and to a bottom position for coaction with groove 27. 100

When the chain is in its bottom position the device may be grasped by the handle 12 and shaken for vibrating the clappers against the body member to produce clapping. In the top position of the chain the device is 105 locked into inoperative condition.

While I have shown and described the preferred embodiment of my invention, it is to

be understood that I do not limit myself to the precise construction herein disclosed and the right is reserved to all changes and modifications coming within the scope of the invention as defined in the appended claims.

Having thus described my invention what I claim as new and desire to secure by United States Letters Patent is:

1. A device of the class described, comprising a mechanical applauder provided with clappers arranged for mechanical vibration upon a body member having a handle and the clappers and handle being provided with ornaments and a chain pivotally connected on the handle and arranged for engaging over the tops of the clappers and the body for pressing the clappers together into inoperative positions.
2. A device of the class described, comprising a mechanical applauder provided with clappers arranged for mechanical vibration upon a body member having a handle and the clappers and handle being provided with ornaments and a chain pivotally connected on the handle and arranged for engaging over the tops of the clappers and the body for pressing the clappers together into inoperative positions and for engaging over the lower end of the handle for assuming an inoperative position.
3. A device of the class described, com-

prising a mechanical applauder provided with clappers arranged for mechanical vibration upon a body member having a handle and the clappers and handle being provided with ornaments and a chain pivotally connected on the handle and arranged for engaging over the tops of the clappers and the body for pressing the clappers together into inoperative positions and for engaging over the lower end of the handle for assuming an inoperative position, a mirror being supported on the outer side of one of the clappers.

4. A device of the class described, comprising a mechanical applauder provided with clappers arranged for mechanical vibration upon a body member having a handle and the clappers and handle being provided with ornaments and a chain pivotally connected on the handle and arranged for engaging over the tops of the clappers and the body for pressing the clappers together into inoperative positions and for engaging over the lower end of the handle for assuming an inoperative position, the tops of the clappers being formed with grooves, and the handle being formed with a groove for accommodating the said chain.

In testimony whereof I have affixed my signature.

BENJAMIN ESCOVAR.
